UNITED STATES PATENT OFFICE

140,294

DESIGN FOR A VIOLIN

Edgar Garding, Paynesville, Minn.

Application May 20, 1944, Serial No. 113,701

Term of patent 14 years

(Cl. D56—1)

To all whom it may concern:

Be it known that I, Edgar Garding, a citizen of the United States, residing at Paynesville, in the county of Stearns and State of Minnesota, have invented a new, original, and ornamental Design for a Violin, of which the following is a specification, reference being had to the accompanying drawings, forming part thereof:

I claim:

The ornamental design for a violin, as shown and described.

EDGAR GARDING.
